UNITED STATES PATENT OFFICE.

JOHN J. SCHAILL AND ALEXANDER G. LEVALLEE, OF TUSLER, MONTANA.

FOLDING PLATFORM FOR GRAIN-BINDERS.

SPECIFICATION forming part of Letters Patent No. 688,128, dated December 3, 1901.

Application filed June 27, 1901. Serial No. 66,239. (No model.)

To all whom it may concern:

Be it known that we, JOHN J. SCHAILL and ALEXANDER G. LEVALLEE, citizens of the United States, and residents of Tusler, in the 5 county of Custer and State of Montana, have invented a new and useful Folding Platform for Grain-Binders, of which the following is a full, clear, and exact description.

The purpose of the invention is to provide 10 a folding platform for grain-binders so constructed that it may be conveniently and quickly folded up to occupy a minimum amount of room or so that the binder may pass through as small a space as that required for 15 the passage of a wagon or like vehicle and so that the platform may be readily and expeditiously lengthened out for use.

A further purpose of the invention is to accomplish the foregoing objects without adding 20 materially to the weight of the platform and to provide means whereby the binder-platform may be folded or unfolded on the field by a youth capable of driving the team drawing the machine.

25 The invention consists in the novel construction and combination of the several parts, as will be hereinafter fully set forth, and pointed out in the claims.

Reference is to be had to the accompanying 30 drawings, forming a part of this specification, in which similar characters of reference indicate corresponding parts in all the figures.

Figure 1 is a plan view of the improved 35 platform in the position for use. Fig. 2 is a rear elevation of the same. Fig. 3 is a rear elevation of the platform folded. Fig. 4 is an outer end view of the platform, the grain-wheel being in engagement with the ground; and Fig. 5 is a transverse vertical section through 40 a part of the platform at the front.

The platform is constructed in a series of sections, four sections being shown in the drawings—two end sections A and A' and two intermediate sections B and B'. Each section 45 of the platform is provided at its front edge on its upper face with an iron 10, preferably Z-shaped in cross-section. The upper member 12 of each Z-iron extends horizontally in a forward direction, and the iron 10, secured 50 to the inner end section A' of the platform, is carried inward beyond the inner edge of the said section, as is best shown in Fig. 1.

The sickle-guards 13 are attached to the upper members 12 of the front irons 10 of the sections of the platform, so that the central 55 sections may be folded upward and the end sections slid toward each other, which is the movement of the sections when the platform is to be closed up or reduced in length. Therefore it will be observed that each section of 60 the platform is provided with an independent series of sickle-guards. The sickle-blade passes over the sickle-guards beneath extensions 13^a from the upper member 12 of the forward iron 10, and this sickle-blade is made 65 so that it may be carried upward without the central sections of the platform. The forward irons 10 of the platform-sections are connected by hinges 14, and at the rear edge of each section of the platform an angle bar or plate 70 15 is secured. These angle bars or plates are connected by suitable hinges 27, as is also shown in Fig. 1.

A body-bar 16 extends from the outer end of the platform, and this body-bar is provided 75 at its center with a slotted standard 17, in which the axle of the grain-wheel 18 is mounted to slide, and said axle is held in adjusted position by a nut 19 or its equivalent. At the central inner section of the bow 16 a 80 socket 20 is formed, and this socket is adapted to receive the standard 21 of a pilot-wheel 22, which turns under the platform. This pilot-wheel is used only when the platform is to be folded, and at such time, as shown in 85 Fig. 3, the grain-wheel is carried up in its supporting-standard 17 and is held in its upper position by an arm 23, which is pivoted upon the bow 16, bearing against the under side of the axle of the main wheel. A suitable keeper 23^a is provided for said arm when it is not in use. When the grain-wheel is thus elevated, it clears all obstructions, and the outer end of the platform is supported by the pilot-wheel only.

Lugs 24 extend upward from the upper members 12 of the front irons 10 of the platform-sections, and bars 25, extending longitudinally of the platform, are secured to these lugs in any approved manner. The bars 25 90 correspond in number to the number of sections in the platform, and their opposing ends are oppositely recessed to overlap a short distance, so that the central sections of the plat-

form may be folded up to the position shown in Fig. 3 without the said bars interfering with one another; but the bar 25, which is carried by the outer intermediate section B 5 of the platform, is connected by a hinge 26 with the bar which is carried by the outer end section A of the platform, the hinge being so placed that this hinged bar 25 may be folded inward, as shown in dotted lines in 10 Fig. 1, and this bar occupies the position shown in dotted lines when the platform is to be folded. Preferably the lugs to which the bars 25, carried by the outer intermediate platform-section B and end section A, are secured are slotted, so that when the hinged bars 25 are to be closed their pins or other bolts may readily enter the openings in the lugs to which they are to be attached.

Corresponding bars 29 are attached to lugs 20 28, formed by the rear irons 15, and the bars 29, carried by the outer intermediate section B and outer end section A of the platform, are connected by a hinge 30, so that the bar belonging to the outer intermediate section 25 of the platform may be carried inward, as shown in dotted lines, when the platform is to be reduced in length, and the bars 29 are raised in like manner as the bars 25, heretofore referred to.

30 A bolt 31 is located at the rear of the platform adapted to prevent the sections from buckling when the platform is in working or horizontal position, and a corresponding bolt 32 is located at the front of the platform, as shown in dotted lines in Fig. 1, below the sickle-guards, the bolts being connected with one section of the platform and their keepers to an adjoining section. These bars 25 and 29 are adapted as supports for the edges of 40 the usual conveyer-apron carried by a platform, and the said belt passes over rollers 33 and 34, journaled in the outer ends of the end bars 25 and 29, as is also best shown in Fig. 1. A winding-roller 35 is journaled in 45 suitable bearings located upon the inner end portions of the inner irons 10 and 15, bracing the platform-sections. At one end of the winding-roller a polygonal section 36 is formed, adapted to receive a wrench or a handle for 50 the purpose of turning the roller, and at this end of the winding-roller a ratchet-wheel 37 is secured, which is engaged by a pawl 38. Cables 39 are secured to the winding-roller 35 and are adapted to be wound thereon. These 55 cables extend along the bottom of the platform and are secured in any approved manner to the outer end section A. Slats 40 are also located at the bottom of the platform. These slats are secured at one end to the 60 outer end section A of the platform, and the said slats at their inner ends have sliding and guided movement in slideways 41, which are secured to the under face of the inner end section A' of the platform. Under this construction it will be observed that when the 65 hinged bars 25 and 29 are carried inward to the dotted position shown in Fig. 1 and the

bolts 31 and 32 are disengaged from their keepers by turning the winding-roller 35 in a direction to wind the cables 39 thereon the 70 end sections of the platform will approach each other, while the intermediate sections will assume the upper inclined position shown in Fig. 3, thereby materially lessening the platform in length and enabling the machine 75 to pass through any opening sufficiently large to permit a vehicle to pass. It is also evident that the platform may be folded or reduced in size on the field and by any person of ordinary strength without undue exertion. 80

When the platform is to be restored to its working position, the pawl 38 is disengaged from the ratchet-wheel 37 and the rear end of the platform is drawn outward, whereupon the weight of the upper ends of the central 85 sections will cause these sections to drop downward practically of their own accord and assume their normal position on the supporting-slats 40.

It will be observed that a platform 90 constructed as set forth need not be materially heavier than an ordinary platform, and said platform will be equally as strong as a platform made in one piece or section.

Having thus described our invention, we 95 claim as new and desire to secure by Letters Patent—

1. A harvester-platform constructed in folding sections having hinged connection, and sickle-guards connected with each hinged section, substantially as described. 100

2. A harvester-platform constructed in sections having hinged connections, and means substantially as described, for drawing the end sections horizontally toward each other 105 for the purpose of reducing the platform in length and elevating the intermediate sections, and locking devices for the platform in its folded or in its working position, as set forth. 110

3. A platform for binders, constructed of a series of sections having hinged connections, sickle-guards in independent series, each series of guards being connected with one section of the platform, locking devices for the 115 platform, and a mechanism substantially as described, for drawing the end sections toward each other and elevating the intermediate sections of the platform, as set forth.

4. A platform for binders, constructed in a 120 series of sections having hinged connections, a grain-wheel, a bearing for the grain-wheel in which it is vertically adjustable, said bearing being connected with the outer section of the platform, a support for the grain-wheel, 125 likewise carried by the outer end section of the platform, which outer end section is also provided with a socket, a pilot-wheel the shank of which is adapted to enter the said socket, and a winding mechanism comprising a winding-roller and cables attached thereto, the cables extending beneath the platform, being attached to the outer end section of the same, 130 as described.

5. In binders, a platform constructed of a series of hinge-connected sections, the end sections being capable of movement toward each other and the intermediate sections capable of an upward movement, means for operating the said sections of the platform, rails at the bottom of the platform, attached to the outer end section, and slideways attached to the inner end section of the platform, in which the 10 said rails have sliding movement, the rails being free from the intermediate sections of the platform, as described.
6. In a binder, the combination, with a platform constructed in a series of hinge-connected sections, and means, substantially as described, for operating the said sections, of sickle-guards secured to the forward end por- 15

tions of the sections, and bars attached to the forward and rear end portions of the sections, being adapted to support the edges of the platform conveyer-apron, one pair at the front and at the rear of the platform being capable of folding inward, and locking devices for the said sections, adapted to hold said sections in horizontal position, as described. 25

In testimony whereof we have signed our names to this specification in the presence of two subscribing witnesses.

JOHN J. SCHAILL.

ALEXANDER G. LEVALLEE.
